Primary Examiner — Garth Rademaker*Assistant Examiner* — Melanie Pellegrini(74) *Attorney, Agent, or Firm* — Dara L. Onofrio, Esq.; Onofrio Law**CLAIM**

The ornamental design for an adjustable bracelet, as shown and described in the drawings.

DESCRIPTION

FIG. 1 is a perspective view of an adjustable bracelet showing my new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is another perspective view thereof.

The broken lines shown in the drawings represent environmental matter and form no part of the claimed design.

1 Claim, 4 Drawing Sheets(56)
